Inventor:
Alfred Knudsen
By June Omiehle
Attorney.

UNITED STATES PATENT OFFICE.

ALFRED KNUDSEN, OF AALBORG, DENMARK.

SOUND AMPLIFIER.

Application filed October 15, 1927, Serial No. 238,471, and in Denmark October 16, 1926.

The horns or amplifiers for gramophones and for radio receiving sets hitherto used very frequently involve the drawback that they cannot be brought to vibrate with exactly the same vibrations as those produced by the music or speech played or broadcast. Hence, it happens that the proper vibrations of the speaking trumpet are heard as special aliquot tones which have a disturbing and sometimes attenuating effect on the tones of the music, so that not all the tones of the piece of music can be heard. The present invention which relates to a horn or loud speaker for gramophones and radio apparatus removes this drawback, so that every tone is heard clearly and distinctly without disturbing aliquot tones.

In the accompanying drawing:

Fig. 1 is a plan view of a loud speaker according to the invention,

Fig. 2 is a section on the line *a—a* of Fig. 1, and

Fig. 3 a section on the line *b—b* of Figs. 1 and 2.

The horn or speaker in question is constructed by gluing together several pieces of wood in each of which is made a hole of a certain form, so that these holes, after the joining of the pieces to a speaking trumpet or horn, are in communication with each other and together form in the interior of the speaking trumpet a cavity suitable for the sound and rather funnel-shaped.

1 is the laminated horn or trumpet which at the top has a hole 2 for coaction either with a tone arm for a gramophone or with a telephone receiver for a radio receiving set. From the hole 2 emerges a nearly funnel-shaped cavity 3 which first passes almost horizontally to the side of the horn opposite to the hole 2, where it merges evenly into a downward sloping cavity 4. This sloping cavity 4 is in communication with an opening 5 lying symmetrically about the vertical center-line of the horn. The cavities 3 and 4 and the opening 5 are of constantly increasing cross-sectional area from hole 2 onward. In order to produce a pure tone the cavities 3 and 4 must have the special form shown.

2 A horn or speaking trumpet like that de-

scribed can be placed in the usual gramophone cabinets. When used for radio receiving apparatus it can likewise be built in the said cabinet or in another one specially constructed, so that there is room for the radio apparatus in the same cabinet.

I claim as my invention:

An amplifying horn, comprising a multiplicity of veneer laminae glued together to form a single unit, said unit having formed through its component laminae a sound passage of constantly-increasing circular cross-section throughout, starting from a relatively small hole in the top of the unit toward one side thereof and terminating in a relatively large outlet opening which extends laterally outward through the front of the unit; the intermediate portion of the passage between said hole and said opening first extending horizontally toward the opposite side of the unit from that in which the hole is located and then sloping downward and merging into said opening.

I testimony whereof I affix my signature.
